R. BRIGGS.
ANTISKID CHAIN.
APPLICATION FILED JAN. 13, 1922.

1,429,674.

Patented Sept. 19, 1922.

FIG. 1.

UNITED STATES PATENT OFFICE.

ROBERT BRIGGS, OF SALIDA, COLORADO.

ANTISKID CHAIN.

Application filed January 13, 1922. Serial No. 528,913.

To all whom it may concern:

Be it known that I, ROBERT BRIGGS, a citizen of the United States, and a resident of Salida, in the county of Chaffee and State 5 of Colorado, have invented certain new and useful Improvements in Antiskid Chains, of which the following is a specification.

This invention relates to fastening devices for anti-skid chains and is an improvement 10 on the construction illustrated in my United States Patent #1,238,631.

In a fastening device constructed in accordance with the aforesaid patent no positive means was provided for holding the 15 end links of the side chains in engagement with the hooks and consequently the end links frequently became disconnected from the hooks thereby permitting the anti-skid device to become disconnected from the 20 tire.

Therefore, a further object of this invention is to provide a fastening device of the type illustrated in the aforesaid patent, the said fastener being provided with novel 25 means whereby the end links of the side chains are at all times held in engagement with the hooks.

Further the invention aims to provide novel means whereby the locking lever of the 30 device may be utilized as a means for holding the end link in engagement with the hook, so that the locking lever or arm will in addition to holding the several parts in a set position act as a means to hold the end 35 links within the bill of the hook.

A further object is to provide a device of the character specified which is of highly simplified construction, durable in use and cheap to manufacture.

40 Other objects and advantages of the invention will be apparent during the course of the following description.

In the accompanying drawing forming a part of this application and in which like 45 numerals are employed to designate like parts throughout the same,

Figure 1 is a side elevation of the improved fastener applied.

Figure 2 is a perspective of the same.

50 Figure 3 is a longitudinal sectional view through the fastener, the view illustrating the locking arm arranged in overlapping relation to the bill of the hook so as to hold the end link within the bill of the hook at 55 all times.

In the drawing wherein for the purpose of illustration is shown a preferred embodiment of the invention, the numeral 5 generally designates a wheel having a felloe 6 about which a tire 7 is arranged. An anti-skid chain 8 is arranged about the tire 7 and is provided with the usual side and cross chains 9 and 10 respectively. 60

The invention forming the subject matter of this application resides in a chain fastening device having an elongated body plate 12 one end of which is apertured as indicated at 13 whereby the terminal link of one end of the side chain 9 may be connected to the body. As illustrated in Figures 2 and 3 a 70 pivot element 14 is extended through the other end portion of the body 12 and is provided with squared ends extended through a locking arm 15 and a link 16. As the locking link 16 and the locking arm 15 are non-75 rotatably connected to the pin 14, the movement of the locking arm will result in the movement of the link 16. Therefore, when the locking arm is swung to a position parallel to the body 12 the link 16 which is arranged in spaced parallel relation to the locking arm will also be swung to a position 80 parallel to the body and on the opposite side from the locking arm. This construction is illustrated in Figure 3 wherein the rear terminal portion of the locking arm 15 is illustrated as having connection with a locking stud 19. The locking stud 19 is extended upwardly 85 from the body 12 and has its end inclined so that when the curved lip 20 is engaged with the same the arm 15 will yield slightly and will ride upon the pin. The continued movement of the locking arm will cause the pin or stud 19 to be received within an opening 22 at one side of the curved lip 20 90 whereby the locking arm 15 is securely held in position on the body 12. 95

One longitudinal edge of the locking arm 15 is formed with lateral extension 23 constituting a finger piece whereby the locking 100 arm may be moved on its pivot. The locking arm is of spring metal and when it is desired to remove the same from engagement with the pin 19, it is merely necessary to force the terminal portion of the locking arm 105 upwardly and over the pin 19.

One end of the link 16 is provided with a hook 26 having its rear portion connected to the link 16 as indicated at 27 and having its forward portion provided with a bill 28 110.

adapted to be engaged with any one of the links of the side chain. In the case of the aforesaid patent the hooks 28 became disconnected from the side chains and to overcome this disadvantage I have formed the bill 28 so that the free end of the same will flatly abut the forward end of the body 12 when the hook is closed. This positively and completely closes the bill so that the 10 terminal link of the side chain cannot be accidentally disconnected. As illustrated in Figure 3 the forward portion of the locking arm 15 extends beyond the forward end of the body 12 and overlaps the terminal 15 portion of the bill so as to brace the same and prevent the bill from being bent. Also the forward portion of the link 15 is extended beyond the forward end of the body and overlaps the terminal portion of the bill so 20 as to form an additional locking means for the bill. The extended end portions of the link 16 and the locking arm 15 define what might be said to be a groove in which the terminal portion of the bill 28 is received 25 so that the bill is positively held in position.

When the parts are in the position illustrated in Figure 1 the terminal portion of the bill 28 flatly contacts with the forward end of the body so that the hook is positively held 30 against pivotal movement when the device is closed.

With reference to the foregoing description taken in connection with the accompanying drawings it will be seen that a hook constructed in accordance with this invention is 35 positive in operation and that the end of the chain cannot become accidentally disconnected from the hook.

Having thus described the invention what 40 is claimed is:—

1. A fastener for a skid chain comprising a body, a link connected to one end of the body, a hook pivoted to said link and having a bill adapted for engagement with one of the 45 links of a side chain, said bill being adapted to flatly abut one end of the body whereby

to close the bill and hold the link of the chain within the bill.

2. A fastener for a skid chain comprising a body, a link connected to one end of the 50 body, a hook pivoted to said link and having a bill adapted for engagement with one of the links of a side chain, said bill being adapted to flatly abut one end of the body whereby to close the bill and hold the link of the chain within the bill, and means whereby 55 said hook and said link may be adjusted.

3. A fastener for a skid chain comprising a body, a link connected to one end of the 60 body, a hook pivoted to said link and having a bill adapted for engagement with one of the links of a side chain, said bill being adapted to flatly abut one end of the body whereby to close the bill and hold the link of the chain within the bill, said link being 65 extended beyond the body and overlapping the bill of a hook.

4. A fastener for skid chains comprising a body, a hook associated with the body and having a bill adapted to abut the body 70 whereby the link engaged by the bill is securely held in position, and a locking arm adapted for operating said hook and having an extended terminal portion overlapping the bill and contacting with the outer side of 75 the same whereby to brace the bill.

5. A device of the character specified comprising an elongated body, a link connected to one end of said body, a hook connected to one end of said link and having a bill 80 adapted to flatly abut the forward end of said body, a locking arm having connection with said link, said link and said locking arm being extended beyond the forward end of the body and overlapping said bill, 85 whereby to brace the bill and close the same and means carried by the body for holding the locking arm in position.

ROBERT BRIGGS.
